AUTOMOBILE

Edward L. Weed, 42 Carter St., Providence, R.I.

Filed Oct. 15, 1959, Ser. No. 57,938

Term of patent 7 years

(Cl. D14—27)

FIG. 4

FIG. 2

FIG. 3

FIG. 5

FIG. 1

Fig. 1 is a perspective view of an automobile showing my new design;

Fig. 2 is a top plan view of the top portion thereof;

Fig. 3 is a section on line 3—3 of Fig. 2;

Fig. 4 is a fragmentary side view of one-half thereof; and

Fig. 5 is a fragmentary end view of one-half thereof.

The dominant features of the design reside in the portions shown in full lines.

I claim:

The ornamental design for an automobile, substantially as shown and described.
